[57] CLAIM

The ornamental design for a hood for an automobile, as shown and described.

DESCRIPTION

FIG. 1 is a top perspective view of a hood for an automobile, showing my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a side elevational view thereof from the right of FIG. 5, the opposite side elevational view being the mirror image thereof.

The supports for the rear of the hood, seen in FIGS. 5, 6 and 7, are not a part of the hood and not a part of the claimed design: they merely serve to render the hood photographable in its use orientation.
